UNITED STATES PATENT OFFICE.

MORTON G. BUNNELL, OF PORTER, INDIANA, ASSIGNOR TO AUSTIN MANUFACTURING COMPANY, OF CHICAGO, ILLINOIS, A CORPORATION OF ILLINOIS.

ELEVATOR.

1,145,971.

Specification of Letters Patent. Patented July 13, 1915.

Application filed May 13, 1908. Serial No. 432,582.

To all whom it may concern:

Be it known that I, MORTON G. BUNNELL, a citizen of the United States of America, and resident of Porter, Porter county, Indiana, have invented a certain new and useful Improvement in Elevators, of which the following is a specification.

My invention relates to elevating apparatus for general use, but adapted more particularly for use in connection with crushers—that is to say, machines for crushing rock or other material, and especially machines of this character that are portable.

The object of my invention is the provision of an improved and highly efficient elevating apparatus that can be readily folded over and above the crusher, when the machine is to be drawn from one place to another, and which can be as readily raised to a working position.

To the foregoing and other useful ends, my invention consists in matters hereinafter set forth and claimed, and illustrated in the accompanying drawings, in which—

Figure 1 is a side elevation of a portable crushing machine equipped with a folding elevating apparatus embodying the principles of my invention. Fig. 2 is a view similar to Fig. 1, but showing the elevator in a folded condition. Fig. 3 is an enlarged detail side elevation of that portion of the elevator to which the raising and lowering wires or other flexible connections are attached. Fig. 4 is a detail section on line 4—4 in Fig. 3. Fig. 5 is a detail plan view of the elevator drive shaft and one of the two bearings in which the same is supported when the elevator is running. Fig. 6 is an enlarged detail section on line 6—6 in Fig. 2. Fig. 7 is an enlarged detail section on line 7—7 in Fig. 2. Fig. 8 is a detail section on line 8—8 in Fig. 7. Fig. 9 is an enlarged detail plan of the windlass for operating the wire or other flexible connection by which the elevator is raised and lowered—that is, unfolded and folded. Fig. 10 is a detail horizontal section on line 10—10 in Fig. 2. Fig. 11 is a detail view, showing the device by which the lower section of the folding elevator is supported in position to receive the crushed rock from the hopper of the crusher.

As thus illustrated, the crusher A may be

of any suitable construction, is mounted on vehicle wheels B, and provided with the usual crushing hopper C. A spout c receives the crushed rock from the said hopper and discharges the same in a downward and rearward direction therefrom. A platform D is supported upon the body of said crusher, and provided with end boards d, as illustrated. Upright rectangular side frames E are mounted upon said platform, parallel with each other and longitudinally of the machine. Braces e connect the tops of said frames with the forward portion of the machine frame. A windlass F is also mounted upon the said forward portion of the frame, and provided with a handle f for operating the same. Gearing f' connects the handle shaft with the said windlass, and a dog and ratchet wheel f'' prevents backward rotation thereof. A pair of sheaves G are mounted on the upper forward portion of the frames E, and a pair of similar sheaves H are mounted upon the upper rear portion of said frames. Operating wires or cables I are trained over said sheaves and wound at their forward ends upon the windlass F. A couple of stay wires or cables J are secured to the upper portions of said frames. The ends of said wires or cables I and J are secured to the elevator K at k, for operating the same, as will hereinafter more fully appear. The said elevator K comprises an upper frame section k' and a lower frame section k'' hinged or pivoted together at k'', this joint or point of articulation being swingingly connected with the board d by means of a pair of links k', which latter are separated and held against lateral motion by bearing portions k'', which are also secured to said end board. A shaft k'' is provided at the upper end of said elevator, which has a roll k'' and a sprocket k''. The lower end of said elevator has a shaft k'' provided with a roll k''. A belt conveyer k''' having suitable buckets is arranged to travel on said upper and lower rolls. Small rolls k'''' for supporting the loaded portion of the elevator are distributed along the length of the upper section of the elevator, and a similar roll k'''' is provided on the lower section, for the same purpose. Upon the lower end of the upper section of the elevator a drive shaft k''' is

mounted in suitable bearings and provided with a sprocket wheel k^{15} , which latter is connected with a sprocket k^8 by means of a sprocket chain k^{16} . This shaft has a pulley k^{17} which, when the machine is running, is belt connected with the pulley L of the crusher. Thus the operation of the crusher automatically operates the elevator.

In use, the shaft k^{14} is supported in bearings k^{18} on the rear end of the crusher frame. These bearings have cap blocks that can be removed to permit the elevator to fold into the position shown in Fig. 2. In folding, the elevator shaft k^{14} swings bodily about two axes, one axis being the axis about which the links k^4 swing, and the other axis being the joint k^3 , as shown more clearly in Fig. 2. The lower section of the elevator frame is held in position by hooks k^{19} thereon that engage a cross bar k^{20} on the crusher frame or body. The elevator frame slides up and down on this cross bar, at a varying angle, when the elevator is raised and lowered. The wires J limit the upward and outward swing of the elevator when the same is raised for use.

The upper section of the elevator frame is provided with a pair of cross bars M , as shown in Figs. 3 and 4, at each side of the elevator. The front end of said bars are provided with sheaves m at or near the point where the wires or cables I and J are attached to said bars. The rear end of said bars are provided with sheaves m' , it being observed that the frame of the elevator is thus disposed midway between the said front and rear sheaves. When the elevator is to be folded, the wires or cables I are pulled over and around the sheaves m' , and the windlass is then operated to wind up the said wires or cables. As soon as the weight of the elevator is swung past the center, so that it begins to fall of its own accord toward the front of the machine, then the operator lets go of the windlass, or rotates the same in the other direction, thus allowing the upper section of the elevator to descend of its own accord to the position shown in Fig. 2. In this position the frame of the elevator rests on the upper edges of the end boards d , as shown, and the wires or cables are then released from the sheaves m' by the simple lowering of the elevator. The section k' fulcrums on the bearings k^5 when the elevator is folded. Thus the lower section k^2 is raised when the upper section is lowered. In this condition the elevator is ready for raising, and as soon as the upper section of the elevator swings up and past the center, then the weight thereof is sufficient to bring the elevator of its own accord into the position shown in Fig. 1. Whether the elevator is to be raised or lowered, the operation is the same as far as the windlass is concerned. In

either case, the operator first winds up the cables and then pays the same out to complete the operation.

What I claim as my invention is:

1. In apparatus of the class specified, an upper section, a lower section, an elevator belt on said sections, a drive shaft on the upper section, bearings for said shaft, means for folding said upper section relative to the lower section, said shaft being releasable from said bearings to permit said folding operation.

2. In apparatus of the class specified, an upper section, a lower section, a connection between the upper and lower sections, a support, links connecting the sections with said support, a shaft on the lower end of the upper section, bearings on said support for said shaft, means for lowering the upper section to a horizontal position, said shaft being releasable from said bearings to permit said lowering operation.

3. In apparatus of the class specified, an upper section, a lower section, links for supporting said sections, bearings engaging said links to prevent lateral motion thereof, means for folding the upper section relative to the lower section, and a releasable support for said upper section to permit folding.

4. An elevator comprising upper and lower sections, means for lowering the upper section; a fulcrum engaging the upper section between the ends thereof, means for raising the lower section by the lowering of the upper section, and a stationary support on which the lower section slides up and down at a varying angle.

5. In an elevator, an upper section, means for supporting the same, a lower section, a hinge connection between said sections, means for folding the upper section downward over the lower section, and a stationary support on which the lower section slides up and down at a varying angle.

6. In an elevator, an upper section, a lower section, means for folding the upper section downward and backward, means acting on the upper section to raise the lower section when the upper section is lowered, and a support on which the lower section slides up and down at a varying angle, the lower sections having hooks for engaging said support when the elevator is unfolded.

7. In an elevator, the combination of an upper section, a lower section pivoted thereto, links for supporting the pivotal connection, means for holding the lower section in position, a shaft on the upper section, a frame, releasable bearings on the frame for said shaft, fulcrum bearings for engaging the upper section to cause it to raise the lower section, when the shaft is released from said bearings, means operated by said shaft for driving the elevator, a winding

mechanism, and connections for raising and lowering the elevator by one and the same mode of operation of said mechanism.

8. A folding elevator comprising a standard, pulleys carried by said standard, a folding elevator frame adapted to extend outward and upward from said standard and to be swung inward over the standard, hoisting mechanism comprising a cable extending between said pulleys and connected with the upper portion of said elevator frame, said cable being arranged to bear on said pulleys when the elevator frame is in operative position and when the elevator frame is swung over said standard, and means for operating said cable.

9. A folding elevator comprising a standard, pulleys carried by said standard, a folding elevator frame adapted to extend outward and upward from said standard, and to be swung over the standard, hoisting mechanism comprising a cable extending between said pulleys and connected with the upper portion of said elevator frame, said cable being arranged to bear on said pulleys when the elevator frame is in operative position and when the elevator frame is swung over said standard, means for operating said cable, and means connected with said standard and with the lower portion of the elevator frame and movable to permit movement of the same toward or from a vertical position.

10. In apparatus of the class specified, an upper section, a lower section, means including a driving shaft for supporting the upper section, an elevator belt on said sections, driven by said supporting shaft, means for folding the upper section downward to a position above the lower section, leaving the lower section in a substantially upright position, a wheeled vehicle, and a frame on the vehicle for supporting the upper section in horizontal position, the lower section extending below the ground line of the wheels when the elevator is in use, said vehicle being movable on its wheels when the upper section is horizontal and the lower section is thereby brought above the said ground line.

11. In apparatus of the class specified, an upper section, a lower section, an elevator belt on said sections, a joint between said sections, supporting links secured to said joint, whereby the lower section is supported at its upper end, means for supporting said links, stationary means for holding the lower section in position, upon which the lower section slides up and down when the elevator is folded and unfolded, means for folding the upper section downward to a position above the lower section, leaving the lower section in a substantially upright position, a wheeled vehicle, and a frame on the vehicle for supporting the

upper section in horizontal position, the lower section extending below the ground line of the wheels when the elevator is in use, said vehicle being movable on its wheels when the upper section is horizontal and the lower section is thereby brought above the said ground line. 70

12. In an elevator, an upper section, a lower section pivoted thereto, means for supporting said sections at the pivotal connection between them, means for manipulating the upper section, to raise and lower the same, fulcrum members for causing the upper section to raise the lower section bodily when the elevator is folded, a body frame, and a transverse bar on which the lower section slides up and down during the folding and unfolding of said elevator. 75

13. In an elevator, the combination of an upper section, a lower section pivotally connected therewith, means for supporting the sections at their pivotal connection, means on the upper section for driving the elevator, including a combined support and driving shaft, a frame having bearings for said shaft, stationary means acting on the upper section to raise the lower section when the elevator is folded, means whereby said shaft has bodily movement about two axes when the elevator is folded, one of said axis being movable about the other and mechanism for folding and unfolding the elevator, by raising and lowering the upper section thereof. 80

14. An elevator comprising a suitable support, an elevator frame comprising upper and lower members hinged together and adapted to extend outward and upward from said support, said members being movable independently of said support, the upper member being adapted to fold over upon said support, and means connecting the lower member with said support and upon which said lower member slides bodily upward when the upper member is folded over upon said support, the angle of said lower member being substantially the same for both positions thereof. 85

15. A folding elevator comprising a suitable support, a folding elevator frame composed of members hinged together and adapted when in operative position to extend outward and upward from said support, means including a driving shaft for supporting and holding said elevator frame in operative position, said upper member being adapted to fold over upon said support, swinging means connecting the lower member of said elevator frame to said support, and movable to permit movement of the same toward or from a vertical position, and hoisting mechanism mounted on said support and connected with the upper member of the elevator frame. 90

16. A folding elevator comprising a suitable support, a folding elevator frame composed of members hinged together, means connecting the lower member of the elevator frame with said support and arranged to permit endwise movement thereof, said upper member being adapted to fold over upon said support, a stationary fulcrum on which said upper member is adapted to bear between its ends when folded over upon said support, and means for driving the elevator, carried on said frame, and adapted to rest in operative position on said support when the elevator is running. 70
17. A folding elevator comprising a suitable standard, a folding elevator frame composed of members hinged together, means connecting the lower member with said standard and arranged to permit endwise movement thereof, said upper member being adapted to fold over upon said standard, and a fulcrum carried by said standard, on which said upper member is adapted to bear between its ends, when folded over said standard, a shaft for operating the elevator, carried on one said member, and means rigid with said standard to engage said shaft and support the elevator in operating position. 75
18. The combination of a carriage, a suitable support mounted thereon, a folding elevator frame comprising upper and lower members hinged together, said upper member being adapted to fold over upon said support, leaving the lower member suspended, stationary means having a sliding engagement with the outer side of the lower member, fixed on said support, and movable means connecting the elevator frame with said support, but permitting said elevator frame to move independently of said support and operated by movement of the upper member into operative position for automatically moving the lower member into operative position. 80
19. The combination of a carriage, a suitable support mounted thereon, a folding elevator frame comprising upper and lower members hinged together, said upper member being adapted to fold over upon said support, leaving the lower member suspended, a fixed horizontal bar upon which the lower member slides up and down when the elevator is folded and unfolded, and means connecting the lower member with the carriage and operated by the movement of the upper member into or out of operative position to move the lower member vertically and carry the lower end thereof toward or from the carriage. 85
20. A folding elevator comprising a suitable support, an elevator frame comprising upper and lower members adapted to cooperate when in operative position, the upper member being adapted to fold over upon said support and having a fulcrum thereon between its ends, means for automatically moving the lower member bodily relative to said support when the upper member is moved into or out of operative position, a shaft mounted for rotation on said support, and means fixed on said frame to serve as bearings for said shaft. 90
21. An elevator comprising a suitable support, an elevator frame comprising upper and lower members hinged together, a fulcrum carried by said support on which said upper member is adapted to turn, and stationary means connecting said lower member with the support, upon which the lower member slides up and down, and whereon the same moves bodily upward when the upper member is folded over upon said support. 95
22. A folding elevator comprising a suitable support, an elevator frame comprising upper and lower members hinged together, adapted to extend outward and upward from said support, swinging links connected with the lower member of said elevator frame at separated points and connected with the support at separated points, whereby said links operate to permit the lower member to move into and out of operative position, means for supporting the upper member upon said support when in its folded position, devices for locking the frame to said support in upright position, said devices being disposed on the upper member, and hoisting mechanism mounted on the support and connected with the upper member, said hoisting mechanism being arranged to operate to lift the upper member both when in its folded and when in its operative position. 100
23. A folding elevator comprising a suitable support, a hinged elevator frame adapted to extend outward and upward from said support, swinging links pivotally connected at different points with said support and with the lower portion of the elevator frame, to permit movement of the same toward or from a vertical position, hoisting mechanism mounted on said support and connected with the upper portion of the elevator frame, and an endless conveyer mounted on the elevator frame, together with a shaft on the back of the elevator frame, connected with the upper end of the elevator, a belt for driving said shaft, and means engaging said shaft to relieve the frame of the weight and pull of said belt. 105
24. In combination with a body frame, a folding elevator, a shaft on said elevator, bearings for said shaft, supported by said frame, having provisions for releasing the shaft to permit folding of the elevator, and links pivoted on the frame, disposed in position to resist gravitational movement of the elevator about said shaft, by endwise compression of each link when the elevator is in 110
- 115
- 120
- 125
- 130

operating position, but permitting the elevator to fold and unfold.

25. A folding elevator, a horizontal driving shaft on said elevator, a stationary support for each end portion of said shaft, having means to permit bodily displacement of the shaft therefrom, when the elevator is folded, and means for supporting the elevator during the folding and unfolding thereof.

26. A folding elevator, provided with a jointed frame, stationary means for engag-

ing said elevator at all times, whereon the elevator frame slides up and down during the folding and unfolding thereof, and a device for engaging said means, secured to the elevator, serving to hold the latter in operating position.

Signed by me at Chicago, Illinois, this 9th day of May 1908.
